CLAIM

The ornamental design for a sprocket, as shown and described.

DESCRIPTION

FIG. 1 is a front perspective view.

FIG. 2 is a front elevation view.

FIG. 3 is a top plan view.

FIG. 4 is a cross-sectional view at line 4-4 in FIG. 3.

FIG. 5 is an enlarged view of the portion marked "A" in FIG. 3; and,

FIG. 6 is an enlarged view of the portion marked "B" in FIG. 2.

The broken lines shown on the sprocket are included for the purpose of illustrating portions of the sprocket which form no part of the claimed design.
